UNITED STATES PATENT OFFICE.

WILBERT L. SMITH, OF SYRACUSE, NEW YORK, AND ADOLPHUS S. DENNIS, OF CLEVELAND, OHIO; SAID DENNIS ASSIGNEE TO SAID SMITH.

SHIPPING-BOX.

1,283,940.

Specification of Letters Patent. Patented Nov. 5, 1918.

Application filed November 3, 1916. Serial No. 129,355.

To all whom it may concern:

Be it known that we, WILBERT L. SMITH and ADOLPHUS S. DENNIS, both citizens of the United States, and residents of Syracuse, 5 Onondaga county, State of New York, and Cleveland, Cuyahoga county, State of Ohio, respectively, have invented certain new and useful Improvements in Shipping-Boxes, of which the following is a specification.

10 This invention relates to receptacles and more particularly to shipping boxes and means for supporting a typewriter or similar machine therein. Heretofore it has been the custom to ship typewriters by attaching them to a rigid rectangular oak board which in turn has been mounted in the shipping box. Obviously, in this method of shipping typewriters, the machine is more or less rigidly subjected to the jars and shocks incident to the handling of the box in transit. 15 The objects of this invention are to provide a means for supporting a typewriter or similar machine in a shipping box in such a manner that it will be yieldingly supported therein, can be easily inserted and removed from the box, and to provide a cheaper means than that heretofore used. Other objects will appear from the description of the device taken in connection with the 20 drawing, in which,

Figure 1 is a bottom plan view of the box with the bottom removed and showing the at present preferred embodiment of the invention;

35 Fig. 2 is a sectional view in elevation taken substantially on the line 2-2 of Fig. 1;

Fig. 3 is a detail sectional view taken on the line 3-3 of Fig. 2;

40 Fig. 4 is a perspective view showing another form of the invention;

Fig. 5 is a sectional view in elevation taken on a line corresponding to 5-5 of Fig. 6;

45 Fig. 6 is a view showing a portion of one end of this form of the shipping box.

As clearly shown in the drawings, the device consists of a box of such a size as to properly inclose the typewriter or other machine and securely hold the frame to which 50 the typewriter is secured. As is well known typewriting machines are provided with four threaded openings in the bottom thereof for screws to be used to secure the machine to a table, desk or other supporting means. The typewriter when being ar-

ranged for shipment is secured to two parallelly arranged strips 10 by means of the screws 12 which engage the before-mentioned openings in the bottom of the typewriter. At their ends the strips 10 are connected by 60 the cross strips 13, which are arranged so that one side of the same will be flush with the ends of the strips 10. Thus the strips 10 and 13 constitute a frame on which the typewriter is mounted. The box 14 in which 65 the typewriter and frame are inserted is made with a removable bottom 15 which may be secured in position by any suitable means. The frame is adapted to be mounted in the box near the bottom 15 and for this purpose 70 cleats 19 are fastened to two opposite sides of the box adjacent and slightly spaced from the said bottom. These cleats are provided with notches 18 which are adapted to receive and form seats for the ends of the 75 strips 10. The cleats 19 and the notches or seats formed therein are arranged so that when the strips 10 are placed in the notches the cross strips 13 will be flush with the bottom edges of the box and consequently in 80 contact with the bottom when it is fastened in position to close the box.

In the form of the invention illustrated in Figs. 4, 5 and 6 the strips 10' having the apertures 11 therein for the screws 12 are of 85 such a length that their ends may be mounted directly in notches or seats 18' formed in the sides 16' and 17' of the box instead of in cleats 19, as in the other form. These notches 18' are of such a depth that when 90 the ends of the strips 10' are placed therein the bottom face of the cross strips 13' will lie flush with the bottom edges of the box so that when the frame is positioned in the box said cross strips 13' will be in contact 95 with the removable bottom 15.

In using the device the frame is secured to the typewriter or other machine and the box is placed in inverted position, that is, with the bottom side upward and open. The 100 frame with the typewriter on the under side thereof is then placed in the box with the ends of the strips 10 or 10' seated in the notches provided for that purpose. The removable bottom 15 is then secured in position to close the box. It will be observed 105 that the machine is mounted on strips which are supported at their ends. Consequently the typewriter is supported in a more or less yielding and springing manner. Any jars 110

or shocks are transmitted to the machine only indirectly and more or less yieldingly. Obviously this frame for this reason is a great improvement over the oak board heretofore used. It will be observed that the notches 18 and 18' prevent movement of the frame in three directions and that the cover or bottom 15 of the box acting against the cross strips prevents movement in the fourth direction. As the machine should be shipped in an upright position the top side of the box may be marked with directions to keep that side upward.

While we have shown and described two methods of supporting the strips 10 and 10' in the box, it is obvious that these strips may be secured against movement and yet supported adjacent their ends in other ways, the only requirement being that the machine be secured to strips which in turn are supported and properly secured against movement adjacent their ends. In this way the springing or beam action of the strips is secured.

Having thus described the invention, what is claimed and desired to be secured by Letters Patent is:

1. The combination with a closed shipping box for machines of the character described, having a detachable bottom, of

Copies of this patent may be obtained for five cents each, by addressing the "Commissioner of Patents, Washington, D. C."

parallel spaced resilient strips and means for securely attaching a machine thereto, seats in the box near the bottom thereof in which the ends of said strips are removably fitted without freedom for horizontal movement, and means for spacing the ends of said strips from the bottom of the box and preventing vertical movement of said ends, the intermediate portions of the strips forming a resilient support for a machine.

2. The combination with a closed shipping box for machines of the character described, having a detachable bottom, of parallel spaced resilient strips and means for securely attaching a machine thereto, seats in the box near the bottom thereof in which the ends of said strips are removably fitted without freedom for horizontal movement, and means for spacing the ends of said strips from the bottom of the box and preventing vertical movement of said ends, including cross strips arranged at the ends of said resilient strips on the side opposite the machine, the intermediate portions of the resilient strips forming a spring support for a machine.

In testimony whereof we affix our signatures.

WILBERT L. SMITH.
ADOLPHUS S. DENNIS.
